UNITED STATES PATENT OFFICE.

HENRY L. FISHER, OF WAYNESBORO, PENNSYLVANIA, ASSIGNOR TO LANDIS MACHINE COMPANY, OF WAYNESBORO, PENNSYLVANIA, A CORPORATION OF PENNSYLVANIA.

NIPPLE-THREADING MACHINE.

1,251,209.

Specification of Letters Patent. Patented Dec. 25, 1917.

Application filed August 13, 1913. Serial No. 784,657.

To all whom it may concern:

Be it known that I, HENRY L. FISHER, a citizen of the United States, residing at Waynesboro, Franklin county, and State of Pennsylvania, have invented and discovered certain new and useful Improvements in Nipple-Threading Machines, of which the following is a specification.

My said invention relates to certain improvements in machines for the manufacture of nipples, its object being to provide a machine of this class for the manufacture of pipe nipples upon which the threads are conical and by which both ends of the nipples may be threaded without removing the said nipple from the machine.

Another object is to provide a machine which will thread a length of pipe and cut the same into the required lengths for such nipples.

A still further object is to provide a machine for either close or spaced nipples, the term "spaced" in this instance meaning a nipple for use between two lengths of pipe which it is desired to space apart.

With this and other objects in view the invention consists of the novel combination and arrangement of parts hereinafter more fully described and illustrated in the accompanying drawings.

Referring now to the accompanying drawings, which are made a part hereof and on which similar reference characters indicate similar parts,

Fig. 1 is a side elevation of a nipple machine embodying the present invention,

Fig. 2 an enlarged transverse section through a portion of the machine looking toward the die head,

Fig. 3 a detail side elevation of the subject matter of Fig. 2,

Fig. 4 an enlarged section of the anti-friction bearing for supporting the nipple while it is being cut,

Fig. 5 an end view of the beveled chaser,

Fig. 6 a face view of the same, and

Fig. 7 a view of a section of pipe after threaded and ready to be cut into nipples.

In said drawings the portions marked A represent the base or frame of the machine, B a cone pulley, and C the head-stock, these features being common in machines of this type and of a well known construction and arrangement.

The die head 1 is mounted in the usual or any preferred manner on a base 2 mounted on a carriage D, which carriage is mounted to be moved longitudinally on the bed of the machine.

A hand wheel 39 on a cross shaft connected by a suitable gearing (not shown) with said carriage provides means for moving or feeding said carriage by hand, while an operating screw 40 connected to driving shaft 41 through suitable gearing (outlined by dotted lines) mounted under hood 42, provides for the feed or longitudinal movement of said carriage by power. Said carriage is geared to said screw through the medium of a half-nut 43 carried by a lever 44 on a pivot 45, said lever being in turn pivoted to the carriage on a pivot 46. On the outer end said lever 44 is provided with a latch 47 adapted to engage a catch 48 on the outer end of the carriage. Said latch 47 is mounted on a pivot 49 and is adapted for slight independent movement so that the operator by grasping the outer ends of said latch and lever may throw the latch out of engagement with said catch. A sliding rod 50 is mounted in perforations in lugs 51 and 52 and a spring 53 is interposed between lug 52 and a collar located an appropriate distance therefrom on said rod which normally holds said rod in a forward position. The rear end of said rod is adapted to strike the face of latch 47 when forced rearwardly and disengage the same from catch 48. A strike 54 is mounted on the frame in a position to contact with the inner end of rod 50 when the carriage has moved to the point where the work is completed. Said rod is thereby forced rearwardly, disengaging latch 47 and permitting a stiff coiled spring 55 to force a plunger 56 (mounted in a vertical socket in part 52) upwardly against the under side of lever 44 and elevate said lever and at the same time elevate the nut part 43, disengaging its threads from the threads of the operating screw 40. By this means the forward feed of the carriage is stopped at the desired point, which occurs at the same time the threading die is opened, as will be presently described.

Mounted upon the die head are a plurality of chaser holders 3 which are pivoted at 4 in order that they may be swung toward

and from the center of the head so as to increase or diminish the distance between the points 5 of the chasers 6. The chaser holders are so connected to the ring 7 of the die head that when said ring is revolved it will cause the points 5 of the chasers to move toward and from each other in the manner previously mentioned. All of the mechanism just described, with the exception of the chase 1, may be of any preferred construction, the details not being claimed in the present application and therefore not described only as necessary to make the operation of the features constituting my said invention clearly understood.

An arm 8 is rigidly connected to one side of ring 7 and extends outward therefrom in a horizontal direction and carries an adjustable screw 9 in its outer end which is provided with a jam-nut 10 by which it may be locked in any desired adjustment. A bracket 22 is secured to carriage D adjacent to the die-head and has a vertical socket 12 in which a plunger is mounted and adapted to reciprocate. The lower end of said screw 9 is adapted to normally rest upon the upper end of said plunger. A pin 14 carried by the plunger 11 and movable within a slot 15 of the sleeve 12 serves to prevent rotation of the said plunger and limit its downward movement. Pivoted to the lower end of the plunger at 16 is an arm 17, the free end of which is bifurcated, and mounted within said bifurcation is a roller 18. A cam 19 is mounted on the bed A beneath the roller 18 and in the path thereof, said cam having two oppositely inclined surfaces 20 upon which the roller is adapted to ride as carriage D moves back and forth. A roller 23 is mounted on the lower end of the bracket 22 and bears against the under edge of ledge 21 and serves to steady the operation of the parts. A stop 26 is adjustably mounted in the side of bracket 22, adjacent to pivoted arm 17, and serves to limit the inward movement of said arm.

It will be apparent from reference to Figs. 2 and 3 of the drawings, that a movement of the carriage D in the direction of the arrow will cause the roller 18 to ride upward upon the incline 20 of the cam 19, causing a like upward movement of the plunger 11 and the arm 8. This movement through the cam ring 7 will cause the turning of the chaser holders 3 upon their pivots 4 and swing the points 5 of the chasers 6 inward contracting the die. When the roller 18 reaches the apex 27 of the cam it will then descend upon the opposite incline 20 allowing a downward movement of the plunger which is followed by the arm 8 causing the chaser points 5 to move outwardly. As the pipe of which the nipples are formed is held in chuck C and passes through the opening 28 of the cutter head

and the carriage D moves back and forth, it will be obvious that the points 5 of the chasers cut away more or less of the pipe as they are moved toward or from the center of the said opening by the above operation 70 and the threaded ends of the nipples will thus be formed tapered or conical. When each nipple is finished the carriage is stopped in its forward movement.

Upon a reverse movement of the carriage 75 D the roller 18 will ride over the inclines 20 without affecting the plunger 11 owing to the pivoted connection 16 between said arm and plunger.

The chasers 6 are provided with double 80 inclined grooved faces 29 with a central longitudinal apex. These faces, together with the contracting and expanding movement of the points 5 of said chasers serve to form a double conical threaded portion 85 30 upon the pipe as will be seen by reference to Fig. 7 of the drawing. These double conical portions are formed along the length of the pipe and may be formed continuously and the pipe cut into lengths suitable 90 for nipples while it still remains in position upon the machine. The pipe is then cut into sections forming the nipples, the cut being made at the smallest diameter of the threaded portion, as on the dotted line 95 x-x, shown in Fig. 7. A blank space 31 may be left between the highest points of the threads to provide for a "spaced" nipple when desired.

The cutting of the pipe into nipple lengths 100 may be performed by any of the well known means, a cutter 32 adapted for this purpose and to operate alternately with the threading mechanism, being shown in a general way only in Fig. 1 of the drawings, being 105 mounted on a carriage 38 adjustable longitudinally of the bed to suit different lengths of nipples.

In order that the threaded end of the pipe may be securely held without damage 110 to the threads while the cutting operation takes place, an anti-friction bearing, shown in detail in Fig. 4, is also mounted on said carriage 38 positioned to receive and support the section of pipe projecting through 115 the die. This anti-friction bearing consists of a circular member 33 located between the cutter head 1 and the cutting off element 32. This circular member is stationary and is provided upon its interior with a rotatable 120 ring 34, said ring being provided with a plurality of raceways 35 for anti-friction balls 36, end rings 37 serving to hold the ring 34 in position. A split bushing 38 adapted to be slightly compressed so as to frictionally engage and rotate with the threaded 125 end of the pipe rests within the ring 34. This construction provides for securely holding the pipe end while being cut into nipple lengths, at the same time allowing 130

said pipe to freely rotate. By providing different sized bushings the same bearing may be used with different sized pipes.

Having thus fully described my said invention, what I claim as new, and desire to secure by Letters Patent is:

1. A nipple making machine comprising a die head, double tapered chasers mounted on said die head, and means for automatically operating said chasers toward and from the center of the die during the process of threading the work.

2. A nipple making machine comprising a frame, a carriage, a die head on said carriage, means for reciprocating said carriage back and forth, chasers pivotally mounted upon said die head, means for automatically closing the die, and means for continuously moving the chasers into and out of the work during operation as the carriage reciprocates back and forth, substantially as set forth.

3. A nipple making machine comprising a die-head, double tapered chasers mounted on said die-head, and means for operating said chasers toward and from the center of the die while cutting.

4. A nipple making machine comprising a die-head, chasers pivotally mounted upon said die-head, said chasers being provided with a double inclined face, and means for automatically moving said chasers upon and in the plane of their supports during operation.

5. A nipple making machine comprising a die-head, double-faced chasers pivotally mounted upon said die-head, and a cam operated mechanism for causing said chasers to move upon their pivots while operating.

6. A nipple making machine comprising a die-head, chasers pivotally mounted upon said die-head, an arm extending from said die-head, and connection between said arm and chasers, a plunger located adjacent said arm and operatively connected thereto, and a cam for operating said plunger.

7. A nipple making machine comprising a die-head, chasers pivoted upon said die-

head, an arm extending from said die-head, and connection between said arm and chasers, a plunger located adjacent to and connecting with said arm, and a double inclined cam for operating said plunger.

8. A nipple making machine comprising a frame, a reciprocating carriage, a die head on said carriage, chasers mounted upon said die head, and means for moving said chasers toward and from the center of the die operated by the reciprocation of said carriage, substantially as set forth.

9. A nipple making machine comprising a carriage, a die-head mounted on the carriage, chasers mounted upon said die-head, a plunger connected to actuate the die-head, a cam for operating the plunger to position said chasers with respect to the work, and means associated with the carriage for steadyng the operation of said working parts, substantially as set forth.

10. A nipple making machine comprising a carriage, means for reciprocating the carriage, a die-head mounted on the carriage, chasers pivotally mounted upon said die-head, a plunger connected to actuate the die-head, and a double cam for automatically operating the plunger through the reciprocations of said carriage to position said chasers with respect to the work, substantially as set forth.

11. A nipple making machine comprising a die-head, a chaser pivotally mounted on the die-head and having double inclined cutting faces for forming screw-threads, and means for automatically moving the chaser to and from the center of the die-head during the process of threading the work, substantially as set forth.

In witness whereof, I have hereunto set my hand and seal at Waynesboro, Pennsylvania this 25th day of July, A. D. nineteen hundred and thirteen.
